LIQUID DISPENSING PUMP

Application filed April 19, 1929. Serial No. 356,524.

The present invention relates to syrup pumps for soda fountains and the like and has for its object to provide a pump which delivers an accurately measured quantity of liquid at each stroke and in which the liquid is discharged in a steady stream during the entire pressure stroke of the pump.

A further object is to provide a pump which maintains the liquid level in the discharge spout at a point slightly below the discharge opening of the spout during the intervals between operation of the plunger so that the discharge from the spout begins immediately upon the beginning of the down stroke of the plunger and is positively cut off at the beginning of the up stroke of the plunger so that spouting and splashing of the liquid due to a rush of liquid through the spout is prevented and dripping of liquid from the spout after the completion of the compression stroke is avoided by the lowering of the level of the liquid to a point below the discharge opening.

The present invention provides a pump which has intake and outlet chambers, the inlet chamber receiving liquid from the container and delivering it to the outlet chamber and the outlet chamber delivering the liquid to the spout. Means is provided for simultaneously varying the capacities of the chambers to draw liquid into the inlet chamber while liquid is being discharged from the outlet chamber and to discharge liquid from the inlet chamber into the outlet chamber during the return stroke.

The variation in the capacity of the discharge chamber is made slightly greater than the variation in the capacity of the intake chamber so that during the return or pump filling stroke, a small quantity of liquid is drawn from the outlet conduit back into the discharge chamber of the pump.

This serves to lower the level of the liquid in the discharge conduit slightly below the level of the discharge opening of the spout and this lowering of the level of the liquid takes place upon the beginning of the return stroke of the plunger so that there is a positive cut-off at the outlet at the completion of the pressure stroke of the pump. Liquid

being maintained in the discharge spout at a level close to the discharge outlet, the liquid will begin to flow from the outlet immediately after the pressure stroke is started. An even discharge is thus obtained during the pressure stroke so that sudden rush of liquid to the discharge spout with the accompanying spouting and splashing of liquid is avoided.

With the above and other objects in view, the invention may be said to comprise the device as illustrated in the accompanying drawings hereinafter described and particularly set forth in the appended claims, together with such variations and modifications thereof as will be apparent to one skilled in the art to which the invention appertains.

Reference should be had to the accompanying drawings forming a part of the specification in which:

Fig. 1 is a side elevation of the pump with a portion of the head broken away and shown in section.

Fig. 2 is a transverse section taken above the pump casing on the line indicated at 2—2 in Fig. 3.

Fig. 3 is a vertical section taken centrally through the pump casing.

Fig. 4 is a section taken on the line indicated at 4—4 in Fig. 3.

Referring to the accompanying drawings, the invention is herein illustrated as applied to a syrup pump of the type employed in soda fountains in which the pump is supported in the syrup receptacle by means of a cover fitting an opening in the top of the receptacle. As shown herein, the pump is provided with a head 1 in the form of a cover adapted to fit an opening at the top of the syrup receptacle 2 and this head is provided with an upwardly extending outwardly inclined spout 3 through which the syrup is dispensed. A pump casing 5 is supported adjacent the bottom of the receptacle by means of a tie rod 6 and a pipe 7 which are connected at their ends to the casing and head, the pipe 7 communicating with the spout 3 through the head. The casing 5 contains a cylinder 8 which has an outlet passage 9 open

ing to the lower end thereof and extending upwardly along the side of the casing 5, the pipe 7 being in communication with the upper end of the passage. On the opposite side 5 of the casing, there is an inlet passage 10 which opens into the cylinder at its upper end and extends down along the wall of the pump casing to the bottom of the casing, an upwardly opening check valve 11 being provided in the lower end of the inlet passage 10 which permits flow of liquid into the casing, but prevents reverse flow.

Within the cylinder 8, there is mounted a plunger 12 to which is attached a plunger rod 13 which extends upwardly through a boss 14 in the top of the casing. The plunger 12 divides the cylinder into an upper inlet chamber and a lower outlet chamber, the inlet chamber communicating with the inlet passage 10 and outlet chamber with the outlet passage 9.

In order to prevent leakage of liquid through the top of the pump casing along the surface of the plunger rod, a bearing ring 15 25 is loosely mounted on the rod 13 between the plunger and the top of the casing. This bearing ring engages with the top wall of the casing on the up stroke of the plunger and provides an effective seal at the end of the up 30 stroke when the pressure in the inlet chamber might tend to force liquid upwardly along the surface of the plunger rod, and through the top of the casing. In order to permit flow of liquid from the inlet chamber to the 35 outlet chamber, a by-pass 16 is provided through the plunger and this by-pass is controlled by a downwardly opening check valve 17, which permits flow of liquid downwardly through the plunger during the up-stroke of 40 the plunger and prevents reverse flow during the downstroke of the plunger.

A by-pass 18 establishes communication between the outlet passage 9 and the top portion of the inlet chamber so that a small quantity 45 of liquid may flow from the outlet conduit into the inlet chamber to supply liquid to the inlet chamber in addition to that drawn through the inlet so as to keep the inlet chamber full of liquid. At the upper end thereof, 50 the plunger rod has a knob 19 by which it may be pushed downwardly to discharge liquid through the spout, the plunger rod extending up through the head 1 a sufficient distance to give convenient access to the upper 55 end of the rod. The plunger rod 13 extends through a sleeve 20 rotatably mounted centrally in the head or cover 1 and this sleeve is internally threaded to receive one or more adjustable threaded bearing members 21 in 60 which the plunger rod is slidably keyed. A coil spring 22 surrounds the plunger rod and is interposed between the bearing members 21 and the knob 19 so that the plunger rod and plunger are automatically returned to their uppermost position after being depressed by 65

pressure on the knob 19. By rotating the sleeve 20, the bearing members 21 may be adjusted up or down and the extent of downward movement of the plunger may be varied to vary the quantity of liquid discharged 70 at one stroke of the plunger.

In the operation of the pump, the plunger is depressed by pressing downwardly on the knob 19, causing an increase in the capacity 75 of the inlet chamber, and consequently, sufficient suction to draw liquid through the inlet passage 10 into the inlet chamber. Upon the upstroke of the plunger, the check valve 17 permits the liquid in the inlet chamber to flow downwardly into the discharge chamber and when the plunger is again depressed, the liquid is forced out through the pipe 7 and discharge spout 3. Starting with the cylinder empty, one or two strokes will be required to fill the pump casing and discharge 80 conduit, and, after the level has been established in the discharge pipe above the bypass, complete filling of the inlet chamber will be insured.

The pump has a differential action by 90 reason of the fact that at each stroke, more liquid is forced from the discharge chamber than is drawn into the inlet chamber. This is for the reason that the variation in the capacity of the discharge chamber is greater 95 than the variation of the capacity of the inlet chamber. When the plunger moves downwardly to the bottom of the outlet chamber, the entire contents of the chamber, i. e., the amount of liquid which it contains when the plunger is in the position shown in Fig. 3 is forced from the outlet chamber. At the same time, the lowering of the plunger increases the capacity of the inlet chamber and draws liquid through the passage 10 into the 100 inlet chamber. The increase in the capacity of the inlet chamber, however, is not as great as the decrease in the capacity of the outlet chamber for the reason that the plunger rod 13 moves down into the cylinder as the plunger 110 is lowered and displaces an amount of liquid corresponding to the volume of the portion of the rod moved into the cylinder. The result is that at each up stroke of the plunger, a portion of the liquid is drawn back from 115 the outlet passage 9 into the discharge chamber, the amount so drawn from the outlet passage corresponding to the difference in the displacement of liquid by the plunger in the two chambers, the volume of liquid so 120 drawn from the outlet passage being equal to the volume of the portion of the plunger rod which moves into the cylinder on the down stroke of the plunger. This back flow into the pump from the outlet conduit causes 125 a positive back flow away from the discharge opening to a level slightly below the opening immediately upon release of the plunger, so that the flow through the outlet of the spout is positively discontinued at the end of the 130

pressure stroke. The level of the liquid in the discharge conduit, however, remains quite close to the opening of the discharge spout and the discharge of liquid from the spout begins immediately at the beginning of the downstroke of the plunger so that the liquid cannot acquire a high velocity in the discharge pipe and spout and spurt through the outlet of the spout as is the case where the liquid is forced from the pump cylinder through an empty discharge conduit.

It will be apparent that the present invention provides a pump which accurately measures the quantity discharged at each stroke which discharges the liquid in a steady stream and which positively cuts off the flow and prevents dripping after the completion of the stroke of the plunger.

Furthermore, it is to be understood that the particular form of apparatus shown and described, and the particular procedure set forth are presented for purposes of explanation and illustration and that various modifications of said apparatus and procedure can be made without departing from my invention as defined in the appended claims.

What I claim is:

1. A pump of the character described having an inlet chamber and an outlet chamber, means for simultaneously and inversely varying the capacities of the two chambers with a greater variation in the capacity of the outlet chamber than in the capacity of the inlet chamber, means for admitting liquid to the inlet chamber while its capacity is being increased and for preventing reverse flow, means for admitting liquid from the inlet chamber to the outlet chamber while the capacity of the outlet chamber is being increased and for preventing reverse flow, a discharge spout communicating with the outlet chamber and positioned above the same, and a by-pass leading from said discharge spout to said inlet chamber permitting said inlet chamber to be completely filled with liquid.

2. A syrup pump comprising a measuring cylinder having an inlet chamber and an outlet chamber, means including a differential plunger interposed between the chambers, for simultaneously and inversely varying the capacities of the two chambers with a greater variation in the capacity of the outlet chamber than in the capacity of the inlet chamber, means for admitting liquid to the inlet chamber while its capacity is being increased and for preventing reverse flow, means for admitting liquid from the inlet chamber to the outlet chamber while the capacity of the outlet chamber is being increased and for preventing reverse flow, a discharge spout in open communication with the outlet chamber and positioned above the same, and a by-pass above said inlet chamber and leading thereinto from said discharge spout to permit a

portion of the undischarged liquid in said spout to flow back into said inlet chamber and fill the same.

3. A syrup pump comprising a head having a discharge spout thereon, a cylinder casing below the head, a pipe connecting the spout with said casing, a plunger rod slideable in the head and extending down into said casing, a plunger in the casing connected to said rod, said plunger having an opening and a check valve controlling said opening, an inlet passage communicating with the cylinder above the plunger, a check valve in the inlet passage and an outlet passage communicating with said pipe and with the cylinder below the plunger.

4. A syrup pump comprising a measuring cylinder having a reciprocating plunger, a discharge spout above said cylinder, a conduit connecting the spout to one end of said cylinder, an inlet at the opposite end of said cylinder, a bypass from one side of the piston to the other, a check valve controlling said bypass, a check valve controlling said inlet, and means for operating said plunger, and a by-pass leading downwardly from said conduit to the inlet side of said cylinder to permit undischarged liquid in said conduit to return and fill the space in said cylinder above said pump.

5. In a syrup pump, a head, a casing supported below said head and having a cylinder closed at its ends, a discharge passage adjacent a side of said cylinder and opening thereto at the lower end thereof, and an inlet passage adjacent a side of said cylinder, said inlet passage extending from adjacent the bottom of the casing and opening into said cylinder at the upper end thereof, a piston in said cylinder, and means for actuating said piston.

6. In a syrup pump, a head, a casing supported below said head and having a cylinder closed at its ends, a discharge passage integrally formed with and adjacent to a side of said cylinder, said passage communicating with said cylinder at the bottom end thereof, and an inlet passage integrally formed with and adjacent said cylinder, said inlet passage extending from adjacent the bottom of said casing and opening into said cylinder at the top end thereof, a piston in said cylinder, and rod means extending through the top of said casing for actuating said piston.

7. In a syrup pump, a head, a casing supported below said head and having a cylinder closed at its ends, a discharge passage adjacent a side of said cylinder and opening thereto at the lower end thereof, an inlet passage adjacent a side of said cylinder, said inlet passage extending from adjacent the bottom of said casing and opening into said cylinder, rod means extending through said casing for actuating said piston, and a remov-

able cap portion in the lower end of said casing to permit cleaning of said cylinder.

8. In a syrup pump, a head, a casing supported below said head and having a cylinder closed at its ends, a discharge passage adjacent a side of said cylinder and opening thereinto at the lower end thereof, an inlet passage adjacent a side of said cylinder, said inlet passage extending from adjacent the bottom of said casing and opening into said cylinder, having a by-pass valve operable on the up stroke to permit liquid to flow from the upper to the lower end of said cylinder, rod means extending through the top of said casing for actuating said piston, and a check valve in said inlet passage operable on the down stroke of said piston to permit liquid to enter the upper side of said cylinder above said piston.
9. In a syrup pump, a head, a casing supported below said head and having a cylinder closed at its ends, a discharge passage adjacent a side of said cylinder and opening thereinto at the lower end thereof, an inlet passage adjacent a side of said cylinder, said inlet passage extending from adjacent the bottom of said casing and opening into said cylinder, having a by-pass valve operable on the up stroke to permit liquid to flow from the upper to the lower end of said cylinder, rod means extending through the top of said casing for actuating said piston, a check valve in said inlet passage operable on the down stroke of said piston to permit liquid to enter the upper side of said cylinder above said piston, and a by-pass providing communication between said discharge passage and the side of said cylinder above said pump, whereby liquid may flow from said passage to fill the chamber at the inlet side thereof.

In testimony whereof I affix my signature.
THEODORE H. SCHUTT.
